UNITED STATES PATENT OFFICE.

ALBERT E. KNEE, OF BLUEFIELD, AND GORDON B. HOPKINS, OF LEX, WEST VIRGINIA.

MECHANICAL LONG-WALL COAL-LOADING CONVEYER.

1,343,369.

Specification of Letters Patent. Patented June 15, 1920.

Application filed July 21, 1919. Serial No. 312,345.

To all whom it may concern:

Be it known that we, ALBERT E. KNEE, a citizen of the United States of America, and a resident of Bluefield, in the county of 5 Mercer, in the State of West Virginia, and GORDON B. HOPKINS, a citizen of the United States of America, and a resident of Lex, in the county of McDowell and State of West Virginia, have invented certain new 10 and useful Improvements in Mechanical Long-Wall Coal-Loading Conveyers, whereof the following is a specification.

This invention relates to an apparatus for conveying and loading coal directly from 15 a long-wall face inside the mine to the mine cars in an entry of the mine after such coal has been undercut and shot down.

The object of the invention is to avoid 20 the slow and expensive hand loading usually employed in mines of this character and also to avoid the laying of tracks for mine cars along the working face and to reduce skilled mine labor to a minimum.

The apparatus comprises a continuous 25 conveying means operative along the long-wall face, usually of one hundred and fifty to two hundred feet in length, to rapidly gather the shot-down coal and deliver it at the entry to the cars therein; the gathering 30 means being automatically moved toward the mine face as the shot-down coal in front thereof is gathered up and conveyed away.

Figure 1 of the accompanying drawings 35 represents a plan of a section of a coal mine and an embodiment of this invention in operative position across a long-wall face preparatory to the gathering of the shot-down coal after the undercutting and shooting has been completed.

40 Fig. 2 represents on an enlarged scale a cross section of the mine wall and an end elevation of one of the buckets of this machine in position for starting the gathering operation.

45 Fig. 3 represents a plan view of the mine section and apparatus similar to that of Fig. 1, showing the position of the gathering mechanism after the coal of one undercut has been conveyed out and the mine 50 face cleaned up ready for another cut.

Fig. 4 represents on a large scale a cross section similar to Fig. 2 showing a bucket in position after the coal has been cleaned up or loaded out.

55 Fig. 5 represents on a large scale a plan of one end of the machine.

Fig. 6 represents a longitudinal section thereof on line 6—6 of Fig. 5.

Fig. 7 represents a side elevation thereof.

Fig. 8 represents an end elevation thereof 60 partly in section.

Fig. 9 represents on a large scale a plan of the opposite end of the machine.

Fig. 10 represents a side elevation thereof.

Fig. 11 represents a longitudinal section 65 thereof on line 11—11 of Fig. 9.

Fig. 12 represents a perspective view of one of the series of coal gathering buckets which are dragged across the mine face.

The same reference numbers indicate corresponding parts in the different figures.

This invention is illustrated in connection with an ordinary type of soft coal mine in which the seam of coal is cut by a main entry or passage A, a passage B parallel therewith and a cross passage C connecting said parallel passages. The opposite sides of the cross passage C constitute long-wall mine faces D and E. As shown in Fig. 1 the dotted line f indicates an undercut portion of the mine face D, the coal from which after being shot down is conveyed away during one setting of the machine. In Fig. 2 the space between the lower line g and the horizontal line h indicates the undercut of the mine face, and that portion between the vertical dotted lines i and k indicates a section of coal to be shot down and conveyed away at a single setting of the machine.

90 The machine includes two similar cages 10 and 30 stationed in the parallel passages A and B adjacent the long-wall mine face D and in part opposite the cross passage C. The cage 10 is preferably in the form of an elongated rectangular frame constructed of angleiron bars 11 partially inclosed by a solid sheet iron bottom 12 and solid sheet iron ends 13, both sides and the top and bottom being open along its length. Two longitudinal screw shafts 14 and 15 are disposed within the cage 10 preferably one above the other in the same vertical plane and at about the mid-width of the cage. These screw-shafts rotate in bearings at opposite ends 100 of the cage and are respectively provided at one end thereof with gears 16 and 17. A stub shaft 18 is supported in a bearing at the same end and provided with a large gear 19, disposed between said gears 16 and 17 and meshing with both of them. A longitudinal grooved shaft 20 is also journaled

in bearings at opposite ends of the cage 10. A sliding worm wheel 21 splined on this shaft is movable thereon longitudinally thereof, and serves as a means for rotating said shaft, said worm wheel being actuated as hereinafter described. A gear 22 on shaft 20 meshes with an idle pinion 23 which engages the large gear 19 whereby motion is communicated to the screw shafts 14 and 15.

10 The stub shaft 18 carrying said large gear is provided with a crank 24 whereby said screw shafts may be manually operated.

The cage 30 is similar in general construction to the cage 10. Longitudinal screwshafts 31 and 32 correspond with the screwshafts 14 and 15. The shafts 31 and 32 are respectively provided with gears 33 and 34 which are driven by an intermediate large gear 35 on a stub shaft 36 carrying a 20 crank 37 for manual operation. A grooved shaft 40 carries a slideable worm wheel 41 splined thereon. This shaft has at its outer end a fixed gear 42 which meshes with the large gear 35 and mechanically operates the screwshafts.

Two traveling carriages 50 and 70 are disposed in the cages 10 and 30 respectively and adapted to travel in unison from end to end thereof. The carriage 50 has a U-shaped pan or runway 51 and the carriage 70 has a corresponding U-shaped pan or runway 71. The open ends of these runways are provided with downwardly inclined flaring spouts 52 and 53 and 72 and 35 73 respectively, the runways being so disposed that the spouts of one runway face the corresponding spouts of the other runway. These runways preferably consist of angleiron frames having sheet iron sheathings at top, bottom and sides. The carriage 50 is provided at opposite sides with fixed threaded screw-eyes 54 and 55 through which the screwshafts 14 and 15 of the cage 10 pass, and the carriage 70 is 40 provided at its opposite sides with fixed screw-eyes 74 and 75 which are engaged by the screwshafts 31 and 32 of the cage 30. The runway 51 has at its closed end in its bottom a delivery opening 56 or other 45 suitable delivery means. The top edges of the runway opposite said opening are preferably higher so as to lift the buckets for dumping as hereinafter described.

The carriage 50 carries a reversible electric motor 57, having a driving shaft 58 provided with a worm 59. This shaft carries a worm 62 which engages the worm wheel 21 which slides on the grooved shaft 20. Any suitable means are provided for 50 causing this sliding worm wheel to move with the carriage 50. Motion is communicated through this worm wheel and the mechanism hereinbefore described to the screw-shafts of the cage 10, whereby the 60 carriage is made to traverse said cage from

end to end thereof. The shaft 60 carries near its upper end a gapped pulley or sprocket wheel 63 splined thereon. A sliding clutch 64 on said shaft engages or releases the clutch hub of said wheel to cause 70 it to turn with said shaft or remain loose thereon. A clutch lever 65 actuates said clutch.

The carriage 70 is provided with a vertical shaft 76 which carries a fixed gapped pulley or sprocket wheel 77. The shaft 76 receives motion through this pulley. The shaft 76 carries a worm 78 which engages and drives the sliding worm wheel 41 which slides on the shaft 40 in unison with the carriage movement in the cage 30. An endless cable 80, preferably in the form of a wire rope or chain is passed over the horizontal pulleys 63 and 77 and connects the two parts of the machine disposed at 80 opposite ends of the long-wall mine face. The inner run of this cable passes adjacent to and substantially parallel with said face. The cable is preferably constructed in detachable sections hooked together so that 90 it may be lengthened or shortened as circumstances may require. The cable is preferably provided at intervals with a series of pulley buttons or clamps 81 which engage ends of the peripheral sections of the 95 gapped pulleys. Other means of preventing slipping of the cable under load may be provided. A series of drag buckets 90 are connected by drag chains or ropes 82 to the endless cable 80, preferably at the 100 points of connection therewith of the buttons or clamps 81. These buckets travel in an endless circuit under the pull of the endless cable 80, passing along their inner operative run adjacent to the mine wall 105 face, along their outer inoperative run in a path parallel therewith, at one end through the U-shaped runway 51 of the carriage 50 and at the other end through the U-shaped runway 71 of the carriage 70. These drag 110 buckets are of any suitable construction which adapts them as they pass along the wall face on their inner run to gather coal shot down from said face and deliver it through the opening 56 or at any other desired point. The drag bucket in its preferred form is an automatic dumping bucket having a self-operative drop bottom, and consists when constructed as shown in Fig. 12 of a rectangular box 90 115 having an elongated bottom 91 projective at its front end, the front ends 92 of the side walls being inclined rearward from the bottom to the top. This box is preferably constructed of reinforced sheet metal 120 and is open at its front end. The bottom 91 is supported on a transverse hinge 93 which is disposed forward of the mid-length of said bottom. The greater weight 125 of material on the longer portion of the 130

- bottom behind the hinge causes said longer portion to swing downward and the shorter portion in front of said hinge to swing upward, and all the coal slides off at the depressed rear end of said bottom through the delivery opening in the bottom of the runway when the bucket passes said opening. The bucket is provided at its top on opposite sides with lateral supporting lugs 94 which engage and slide on the top edges of the sides of the runways during the passage of the buckets therethrough. The drag rope 82 is connected with the bucket 90 at the front top portion thereof by a bail or branches 83. The bucket is preferably provided with means to avoid friction in passing through the runways. This means may consist of antifriction rollers 95 disposed at the corners.
- 20 An inclined endless conveyer 100, conventionally shown in the drawings, has a horizontal lower extension 101 projected underneath the delivery opening of the runway 51 and a horizontal upper extension 102 projected over the top of the train of mine cars. This auxiliary conveyer takes the coal gathered by the drag buckets and delivers it into the mine cars.
- 25 The cages 10 and 30 when placed in position are supported by a series of screw-jacks 110 or other suitable means and properly leveled.
- 30 Means are provided for adjusting the relative positions of the cages with a view of tightening the endless cable 80. For this purpose the cage 10 is provided at one end with a drum shaft 25 having a loose gear 26 which meshes with and is driven by the gear 22 of the shaft 20. A clutch 27 on the drum 35 shaft locks said gear to turn therewith when desired. This shaft is provided at its outer end with a rope drum 28. A rope 29 is connected at one end to said drum, wound one or more turns around said drum and connected at its other end to a stake or other fixed point. The cage 10 is also provided at its opposite end with a drum shaft 25' having a loose gear 26' which meshes with and is driven by a gear 22' on the shaft 20. A 40 clutch 27' on the drum shaft 25' locks said gear 26' to turn therewith when desired. This shaft is provided at its outer end with a rope drum 28'. A rope 29' is connected at one end to said drum, wound one or more turns around said drum and connected at its other end to a stake or other fixed point. By shifting the clutches 27 and 27' to lock the gears 26 and 26' the drums 28 and 28' wind or unwind the rope 29 and 29' and tighten 45 or loosen the cable 80. The cage 30 may also be provided with drum shafts 43 and 43' having at their inner ends loose gears 44 and 44' and clutches 45 and 45' for locking said gears respectively. Rope drums 50 46 and 46' at the outer ends of the drum
- shafts 43 and 43' are provided respectively with ropes 47 and 47' which may be connected at their other ends to stakes or other fixed points. The drums are connected with their shafts by friction clutches which yield 70 under excessive stress of the ropes and avoid strain or breakage. These drums at opposite ends of the cage are also to be used in moving the machine across the mine face from one face to another and also for controlling the trip of mine cars as they are being loaded, which latter use avoids the necessity of a motorman and brakeman with their haulage motor waiting while the cars are being loaded.
- 75 In the use of this machine the cages 10 and 30 are fastened in proper positions adjacent to the ends of the long-wall mine face and the carriages 50 and 70 are adjusted in said cages in proper position to 80 bring the operative run of the endless cable 80 adjacent to the loose coal shot down from said wall. Then the machine is started and the drag buckets 90 move in inward direction toward the carriage 50 on 85 the operative run, in outward direction toward the carriage 70 of the inoperative run, and through the runways of said carriages. The buckets gather coal on their inward run, then pass up through the spout 90 95 53 of the runway 51, thence around in said runway to a point over the delivery opening 56 thereof. In passing said opening the bottoms of said buckets owing to the weight of contents therein tilt automatically 100 and dump the contents into the conveyer 100 whence it is delivered to the cars standing on the track of the entry A as shown. The carriages 50 and 70 carrying the endless cable 80 are slowly and continuously moved 105 toward the receding pile of shot down coal by means of the screwshafts of the cages 10 and 30, so as to bring the drag buckets into position for gathering said coal.
- 110 We have illustrated and described the preferred embodiment of the invention but changes may be made therein without departure from the scope thereof.
- We claim as our invention:
1. In an apparatus of the character described the combination of cages adapted to be disposed adjacent to a mine face, carriages movable therein carrying horizontal pulleys, means for actuating said pulleys and arc-shaped runways, an endless cable on said 115 pulleys, a series of individual chains or ropes connected at intervals with said endless cable, and a series of drag buckets connected to the free ends of said individual chains, movable through and between said 120 runways and operative to gather coal shot down from said mine face and discharge it at a point of delivery.
  2. In an apparatus of the character described the combination of cages adapted 125

to be disposed adjacent to a mine face, carriages movable therein carrying horizontal pulleys, means for actuating said pulleys and arc-shaped runways, an endless cable on 5 said pulleys, a series of individual chains or ropes connected at intervals with said endless cable, a series of drag buckets connected to the free ends of said individual chains, movable through and between said runways and operative to gather coal shot down from said mine face and discharge it at a point of delivery, and means for moving 10 said carriages to shift the operative run of said drag buckets toward the diminishing pile of coal.

3. In an apparatus of the character described the combination of cages adapted to be disposed adjacent to a mine face, carriages movable therein carrying horizontal 20 pulleys, means for actuating said pulleys and arc-shaped runways, an endless cable on said pulleys, a series of individual chains or ropes connected at intervals with said endless cable, a series of drag buckets connected to the free ends of said individual chains, movable through and between said runways and operative to gather coal shot down from said mine face and discharge it at a point of delivery, and means for continuously moving 25 said carriages to shift the operative run of said drag buckets toward the diminishing pile of coal.

4. In an apparatus of the character described the combination of cages adapted 35 to be disposed adjacent to a mine face and provided with longitudinal stationary screwshafts, carriages movable therein provided with threaded eyes engaging said screwshafts and carrying horizontal sprocket 40 wheels, operative means therefor and arc-shaped runways, an endless cable on said sprocket wheels, a series of individual chains or ropes connected at intervals with said endless cable, a series of drag buckets 45 connected to the free ends of said individual chains, movable through and between said runways and operative to gather coal shot down from said mine face and discharge it at a point of delivery, and means for turning 50 said screwshafts.

5. In an apparatus of the character described the combination of cages adapted to be disposed adjacent to a mine face, carriages movable therein carrying horizontal 55 pulleys, means for actuating said pulleys and arc-shaped runways having downwardly inclined flaring spouts, an endless cable on said pulleys, a series of individual chains or ropes connected at intervals with said endless cable, and a series of drag buckets 60 connected to the free ends of said individual chains, movable through and between said runways and operative to gather coal shot down from said mine face and discharge it at a point of delivery.

6. In an apparatus of the character described the combination of cages adapted to be disposed adjacent to a mine face, carriages movable therein carrying horizontal pulleys, means for actuating said pulleys 70 and arc-shaped runways, an endless cable on said pulleys, a series of individual chains or ropes connected at intervals with said endless cable, and a series of drag buckets connected to the free ends of said individual chains, movable through and between said runways and operative to gather coal shot down from said mine face and discharge it at a point of delivery, said drag buckets 75 having lateral lugs engaging said runways. 80

7. In an apparatus of the character described the combination of cages adapted to be disposed adjacent to a mine face, carriages movable therein carrying horizontal pulleys, means for actuating said pulleys 85 and arc-shaped runways, one of said runways having a delivery opening in its bottom and elevated guideways opposite said opening, an endless cable on said pulleys, a series of individual chains or ropes connected at intervals with said endless cable, and a series of drag buckets connected to the free ends of said individual chains, movable through and between said runways and operative to gather coal shot down from said 90 mine face and discharge it at a point of delivery, said buckets having lateral lugs engaging said runway and being provided with drop bottoms adapted to operate automatically to dump when over said delivery 95 opening.

8. In an apparatus of the character described the combination of cages adapted to be disposed adjacent to a mine face and provided with longitudinal stationary screwshafts, carriages movable therein provided with threaded eyes engaging said screwshafts and carrying horizontal sprocket 105 wheels, operative means therefor and arc-shaped runways, an endless cable on said 110 sprocket wheels, a series of individual chains or ropes connected at intervals with said endless cable, a series of drag buckets connected to the free ends of said individual chains, movable through and between said 115 runways and operative to gather coal shot down from said mine face and discharge it at a point of delivery, means for turning said screwshafts, and manually actuated means for operating said screwshafts to adjust said carriages. 120

9. In an apparatus of the character described the combination of cages adapted to be disposed adjacent to a mine face, carriages movable therein carrying horizontal 125 pulleys, means for actuating said pulleys and arc-shaped runways, an endless cable on said pulleys, a series of individual chains or ropes connected at intervals with said endless cable, a series of drag buckets con- 130

- nected to the free ends of said individual chains, movable through and between said runways and operative to gather coal shot down from said mine face and discharge it
 5 at a point of delivery, and an endless conveyer having a receiving extension projecting under said point of delivery and a delivery extension projecting over the mine cars.
- 10 10. In an apparatus of the character described the combination of cages adapted to be disposed adjacent to a mine face, carriages movable therein carrying horizontal gapped pulleys, means for actuating said pulleys and arc-shaped runways, an endless cable on said pulleys, provided with buttons engaging gaps of said pulleys, a series of individual chains or ropes connected at intervals with said endless cable, and a series
 15 of drag buckets connected to the free ends of said individual chains, movable through and between said runways and operative to gather coal shot down from said mine face and discharge it at a point of delivery.
- 20 11. The combination of two stationary frames spaced apart from each other, two slidable frames movable in said stationary frames, U-shaped runways disposed in said slidable frames respectively with their open
 25 ends opposite each other, vertical shafts in said movable frames carrying horizontal gapped pulleys, a cable spanning said pulleys, drag buckets connected with said cable and adapted to traverse said runways and
 30 the space between them, and actuating means.
- 35 12. The combination of two stationary frames spaced apart from each other, two slidable frames movable in said stationary frames, U-shaped runways disposed in said movable frames respectively with their open

ends opposite each other, vertical shafts in said movable frames carrying horizontal gapped pulleys, a cable spanning said pulleys, drag buckets connected with said cable and adapted to traverse said runways and the space between them, and means for driving said pulleys and moving said movable frames simultaneously.

45 13. The combination of two stationary frames spaced apart from each other, two slidable frames movable in said stationary frames, U-shaped runways disposed in said slidable frames respectively with their open ends opposite each other, vertical shafts in said slidable frames carrying horizontal gapped pulleys, a cable spanning said pulleys, drag buckets connected with said cable and adapted to traverse said runways and the space between them, means operative to 50 drive said pulleys and move said sliding frames simultaneously, and means for moving said slidable frames independently of the movement of said pulleys.

55 14. The combination of two stationary frames spaced apart from each other, two slidable frames movable in said stationary frames, U-shaped runways disposed in said slidable frames respectively with their open ends opposite each other, vertical shafts in 60 said movable frame carrying horizontal gapped pulleys, a cable spanning said pulleys, drag buckets connected with said cable and adapted to traverse said runways and the space between them, actuating means, 65 and means for adjusting said cages.
